UNITED STATES PATENT OFFICE.

PETER C. BURNS, OF CHICAGO, ILLINOIS.

TELEPHONE-TRANSMITTER.

SPECIFICATION forming part of Letters Patent No. 623,702, dated April 25, 1899.

Application filed January 12, 1899. Serial No. 701,945. (No model.)

To all whom it may concern:

Be it known that I, PETER C. BURNS, a citizen of the United States of America, and a resident of Chicago, Cook county, Illinois, have 5 invented certain new and useful Improvements in Telephone-Transmitters, of which the following is a specification.

My invention relates to certain improvements of a structural character in what are 10 known as "solid-back" telephone-transmitters which employ granular carbon in coöperative combination with the diaphragm as a variable contact medium.

My invention has for its object the provision 15 of means for detachably and firmly holding the various parts of the transmitter intimately together in such a manner as to permit ready and convenient assemblage and detachment and separation of said parts.

20 To accomplish this result, I provide screw-threaded connecting and holding bolts extended from the front or face plate or cover of the transmitter, perforations in the solid back of the transmitter, through which said

25 bolts may pass, locking-nuts on said bolts which engage the said solid back and lock it to the face-plate or cover, with the diaphragm between them, and also perforations in the shell surrounding the solid back, through

30 which the said bolts may pass, with locking-nuts on said bolts engaging the shell. In assembling the parts the bolts fixed on the face-plate are threaded through the perforations in the solid back, with the diaphragm between them, and the locking-nuts adjusted to engage 35

against the solid back and hold it and the diaphragm firmly in position upon the face-plate. Then the bolts are threaded through the perforations of the shell and other locking-nuts adjusted upon the bolts to engage 40 said shell and hold it firmly in a position to inclose about the solid back and engage the face-plate or cover.

Reference may now be had to the accompanying drawings, in which—

Figure 1 is a central sectional view through a transmitter, showing the various parts held together in proper position. Fig. 2 is a view showing the various parts detached and in 45 position to be connected together. Fig. 3 is a front view of the diaphragm, showing con-

ducting-arms secured thereto. Fig. 4 is a detail view of the conducting-arms, the carbon electrode, the detachable connection, and the diaphragm shown separated. 55

The face-plate or cover is designated at A, having connecting-bolts A² A² extended therefrom, screw-threaded to receive two sets of locking-nuts, to be described. The solid back B, of insulating material, which contains and holds the granular material B², is perforated near its edge at B³ B³, and the bolts A² A² pass through these perforations when the solid back B is adjusted in position. The locking-nuts E E are adjusted on the bolts A² 60 A² when the solid back is in position against the face-plate or cover A and screwed firmly against the rear face of said solid back to hold it firmly against the said face-plate or cover. The shell H, inclosing the solid back 65 B, is also perforated at J, and the extended bolts A² A² are likewise threaded through these perforations, and the locking-nuts E E adjusted on said bolts and screwed against the shell to hold it firmly about the solid back 70 B, with its annular edge in engagement with the annular edge of the face-plate or cover A, Fig. 1. By this means the various parts are held securely together. The diaphragm K, 75 interposed between the solid back B and the face-plate or cover A, together with said face-plate and solid back, are all held and locked together by the bolts A² A² and the locking-nuts E E. The shell H is also held securely 80 in position on the solid back and locked in 85 position to inclose the solid back and join with the face-plate. It is obvious that by these means the parts are capable of convenient and ready assemblage and detachment or separation and when assembled are all securely bound and held together. 90

I also provide conducting-arms L L, held on the diaphragm K, which are connected by the detachable screw connection L² with the carbon-plate electrode M, also held on the diaphragm K by said screw connection L². The screw connection and said conducting-arms electrically connect the carbon electrode 95 M with the face-plate or cover A, as the ends of said arms bear upon said face-plate. The diaphragm is isolated by a circular peripheral ring of insulating material N. 100

Having thus described my invention, what I claim as new therein, and desire to secure by Letters Patent, is—
In a telephone-transmitter a face-plate, or cover, bolts secured to and extended from said face-plate, a solid back piece, having perforations therein through which the said bolts pass, locking-nuts on said bolts engaging against the solid back and holding it tightly and securely to the face-plate, or cover, a diaphragm held between said solid back and face-plate by the means aforesaid, an inclosing

shell having perforations therein, through which the said bolts pass, and locking-nuts on the bolts engaging against said shell and holding it securely and tightly about the solid back and in joined connection with the face-plate, or cover.

Signed by me, at Chicago, Cook county, Illinois, this 9th day of January, 1899.

PETER C. BURNS.
